ABSORPTION REFRIGERATOR MECHANISM

Edmund E. Allyne, Cleveland, Ohio, assignor to
Allyne Laboratories, Inc., Cleveland, Ohio

Application January 3, 1938, Serial No. 183,042

8 Claims. (Cl. 62—118)

This invention relates to refrigerators and more especially to the intermittent absorption type, wherein the refrigerating mechanism is a self-contained unit and removable as such from a refrigerator cabinet.

It has been the practice in the past to construct the refrigerating mechanism in separate sections, placing the sections in the refrigerator cabinet and into the several compartments provided therefor, and when in position to then connect the system in operative relation.

This method of construction makes it difficult to service the unit in the field or to remove the unit mechanism as a whole from the cabinet for repairs and later to replace the unit in the refrigerator cabinet.

The present invention provides a self-contained unit that may be constructed and fabricated as such, reducing the cost of manufacture and assembly.

An object therefore of the present invention is to provide an intermittent absorption refrigerating system, fabricated in one unit and slideable into a refrigerator cabinet after which it may be secured in place.

Another object of the present invention is to provide a refrigerator cabinet having an insulated food chamber and mechanism compartments above, below and at the rear of the said food chamber, an opening in one wall of the said chamber to permit freezing members of the unit to project therethru, and sealing means associated with the said freezing members, the said sealing means providing a closure for the opening in the said wall of the food chamber.

A still further object of the present invention is to provide a refrigerator cabinet having a food chamber therein, insulation surrounding the food chamber, an opening in one wall of the food chamber, a mechanism compartment above the said chamber for the reception of an evaporator of the system, a mechanism compartment at the rear of the food chamber, and a mechanism compartment below the food chamber, the compartment at the rear of the food chamber being provided to receive the various conduits of the system, including a rectifier or dehydrator, and the compartment below the food chamber being provided to receive the generator absorber, condenser and cooling coils, together with the heating means such as gas or fuel burner. Freezing coils associated with supply conduits depending from the evaporator and associated therewith, the said freezing coils being provided with a closure member, the said closure member being of greater

overall dimensions than the opening in the wall of the food chamber and means for securing the closure member to the wall of the food chamber. The entire unit including all of the above mentioned elements being fabricated as one unit and movably installed or removed from the refrigerator cabinet.

A further object of the present invention is to provide an intermittent absorption refrigerator system having a refrigerator cabinet and provided with an insulated food chamber, and mechanism compartments exteriorly of the said chamber in which is located the various conduits and mechanism of the system, the said compartments being located above, at the rear of, and below the said food chamber, and an intermediate flue compartment between said rear compartment and said lower compartment to permit air to flow therebetween, thus providing an air insulated space between the mechanism of the system and the outer wall of the food chamber.

Another object of the present invention is to provide suitable air cooling means for the mechanism of an intermittent absorption refrigerator system wherein air flues are provided in the refrigerator cabinet, the air being induced to flow by means of the heat applied to the system and so arranging the flues and compartments as to provide efficient air cooling for the mechanism therein.

Another object of the present invention is to provide a refrigerator cabinet for an intermittent absorption refrigerator system having therein an insulated food chamber, compartments above, at the rear and below the said chamber and air flues arranged in the rear and lower compartment and a housing enclosing the sides of a generator absorber and heating means for the said generator absorber. The bottom portion of the enclosure being open and the top portion of the enclosure opening into a flue member the said flue member being in open communication and associated with air flues in which are located the circulatory coils of the system including the condenser, and providing therefor an induced flow of air, the air being induced to flow by means of the heat applied to the generator absorber of the system, the cool air being induced to flow upwardly through the said flues by the induction of the heated air from the generator absorber.

Other and further objects of the present invention will be more fully understood from the following description when taken in connection with the drawings in which:

- Fig. 1 is a front elevational view of a refrigerator cabinet showing fragmentary views of the interior of the cabinet and the mechanism contained therein.
- Fig. 2 is a side elevational view of a refrigerator cabinet showing an absorption refrigerator system and the location of the various members in dotted lines.
- Fig. 3 is a side elevational view of the complete unit of an intermittent absorption refrigerator system.
- Fig. 4 is a rear elevational view of a refrigerator cabinet being provided with an intermittent absorption refrigerator system.
- Fig. 5 is a segmental top plan view of a refrigerator cabinet being provided with an intermittent absorption refrigerator system.
- Fig. 6 is a fragmental sectional elevational view of support means provided for the cooling coils of the condenser.
- Fig. 7 is a fragmental view of the clip clamp means for securing the removable back portion of the cabinet in position.
- Fig. 8 is a fragmental side view showing the evaporator, supply legs and freezing coils enclosed in insulation, and closure means secured to the freezing coils.
- Fig. 9 is a fragmental rear view of the refrigerator cabinet showing the opening in the rear wall of the food chamber thru which the freezing coils project and the means for securing the closure plate thereto.
- Fig. 10 is a fragmental front view of the food chamber showing the freezing coils and closure plate in place.
- Fig. 11 is a fragmental sectional side view taken on lines 11-11 of Fig. 1 and showing the generator absorber, fuel burner, fuel supply mechanism and circulatory coils of an intermittent absorption refrigerator system.
- Fig. 12 is a top plan sectional view of the generator absorber and circulatory coils taken on lines 12-12 of Fig. 11.
- Fig. 13 is a top plan sectional view showing a portion of the insulation surrounding the food chamber and the rear mechanism compartment and taken on lines 13-13 of Fig. 11.
- Fig. 14 is a side view of the generator absorber, circulatory coils therefor and the condenser receiver and circulatory coils positioned below the said receiver.
- Fig. 15 is a rear view of the generator absorber, circulatory coils therefore and the condenser receiver having circulatory coils therefore located below the said receiver.
- Fig. 16 is a side view of the generator absorber, circulatory coils therefore and the condenser receiver and circulatory coils therefore located above the said receiver.
- Fig. 17 is a modified rear view of the generator absorber, circulatory coils therefore and condenser receiver and circulatory coils therefore, the said coils being located above the said receiver.
- Referring now to the drawings by numerals and reference wherein like numerals correspond to like parts, the reference numeral 5 is a refrigerator cabinet being provided with side walls 6 and 7, a front 8, a top portion 9, and a base 11, the said base being provided with legs 12 of any conventional styling providing that a space 13 between the base portion 11 and the floor be open to permit air to enter therebetween. The side walls 6 and 7 of the cabinet 5 are provided at their rear portion with inturned edges 14 and 15, having spaced apart holes 16 near the edges thereof, the said holes being preferably threaded therein to receive screws 17 or similar conventional securing means, the said screws being provided to secure a back wall 18 to the cabinet side walls, thereby providing a removable rear wall. It should be noted that the top 9 of the cabinet is provided at its rear with a turned down edge 19, the purpose of which will be apparent as the description of the construction progresses.
- It should be further noted that the base portion 11 of the cabinet is provided with inturned flanges 21. The walls of the cabinet are also provided with inturned flanges 22. It should be noted that both of the above mentioned inturned portions are provided with holes (not shown) the said holes registering and through which fastening means such as bolts 23 are secured rigidly in place by means of nuts 24. It should be also noted that the above mentioned flanged portions 21 and 22 form means for the support of various mechanisms of the system. The upper portion of the front wall 8 of the cabinet 5 is provided with an opening 25, the said opening being provided with a door 26 having conventional hinges 27 and exterior unlatching means 28 (the latching means not shown). The door is of the conventional refrigerator door design and provided with efficient insulation therein, the door being so arranged with the opening to thereby provide a tight closure and prevent the entrance of heat therethrough.
- A second opening in the front wall of the cabinet is provided at 29 and is located in the lower portion of said front wall. A closure means 31, having inturned edge portions 32 the said inturned edge portions abut the front wall of the cabinet at 33. Suitable hinge means (not shown) are used for the said closure, thus providing means for access to the lower mechanism compartment.
- The cabinet 5 is provided with a food compartment or chamber 36 having an open front portion 37, a ceiling 38, a floor 39, side walls 41 and 42, the said side walls are parallel to side walls 6 and 7 respectively, and a rear wall 43. It will be noted that the food chamber front portion connects to and forms a part of the front wall of the cabinet, thus making a rigid box like structure and providing complete support from the front wall of the cabinet for the food chamber.
- It is preferred to provide the rear wall 43 of the food chamber with an opening 44, the opening however, may be provided in the ceiling or in one of the side walls without departing from the spirit of the invention. The edge portion 45 of the rear wall 43 is formed with an inset 46, the said inset being provided with spaced apart holes 48 therein, the purpose of which will be discussed in detail later.
- It should be noted that the food chamber is completely surrounded by insulation 47. A portion 48 of the insulation is formed in an L shape and removable from the balance of the insulation, this removable L shaped insulation 48 forms an important member of this invention and will be discussed and described in detail under the mechanism description.
- The insulation 47 is supported in the space between the walls by an outer housing 49, and is secured to the walls 6 and 7 of the cabinet; the front edge of the housing is secured at the front of the cabinet to the front wall 8 by any conventional means such as welding or the like.

The side edges 51 being inturned at right angles to the housing and secured to the inner walls of the cabinet by any suitable means such as electric spot welding. The outer housing 49 terminates at the junction 52 of the insulation 41 and 48. The side walls of the food chamber are provided in spaced apart relation to the side walls of the cabinet, and the ceiling 38 is also in spaced apart relation to the top 9 of the cabinet, and as above stated, with the exception of the front opening 25 and L shaped removable insulation 48. The food chamber is provided with a conventional type insulation completely surrounding the same.

It should be further noted that the outer housing 49 is provided opposite the junction of walls 43 and 39 with a radius 53, the purpose for which will be described later. A rear retainer plate 54 is provided to securely hold the insulation block 48 in place, the said retainer plate being secured at its upper portion by the flange 19 and by any suitable means such as screws, etc. (not shown). The lower portion of plate 54 is secured to the outer housing 49 by screws 60, or similar means.

A downwardly curved directional baffle 56 is secured at its upper portion to an angle member 57, one leg of the angle member being secured to the outer housing 49 by any conventional means such as screws (not shown), the curved baffle member terminates approximately midway between the outer housing 49 and the base 11. The said curved baffle member opposite the wall is provided with a bend 57a inwardly directed, and forms a perpendicular baffle wall 58, which is provided with conventional insulation 59. The wall 58 is again bent at right angles and directed toward wall 7 of the cabinet, and continues as a baffle wall 55 and in parallel relation to the curved portion 56, terminating at an inner wall 61.

The said inner wall 61 is in spaced relation to the side wall 7 of the cabinet, being secured at one end to the flange 15. The said inner wall 61 continues for a distance and toward the front of the cabinet, beyond the junction of the connection of wall 55, at which point it is bent at right angles forming a baffle wall 63 terminating at the wall 58, and secured thereto, thus forming a box like housing. The baffle wall 63 continues upwardly and rearwardly, and in spaced relation to the baffle 56 and the housing 49 terminating in a radius 67 adjacent the radius 63 and conforming thereto and in spaced relation therewith. From a line opposite the terminus of the baffle 56, insulation 68a of any conventional type is secured to the upper side of the wall 63 and terminates at or near the radius terminal 67. An opening 68 is provided in the front portion of the wall 63, the said opening is provided with a door 69 and with hinges 71 at the lower portion thereof and clamping or detaching means 72 at its upper portion, and is also provided with a handle 73.

A stack member 76 is provided at the rear of the cabinet, the upper portion being formed in a channel shape, the leg 77 terminating adjacent the rear wall 18, and the leg 78 of the channel terminating adjacent the flange 15 of the cabinet wall 7. The wall 76 continues downward and is secured by any suitable means to the terminal 67 of the baffle 63. One leg of the channel continues downwardly to a point slightly below the above mentioned terminal 67, and is then provided with an angular bend at 79, and toward the cabinet wall 6, continuing downwardly to form an inclined baffle 81. At a point approximately in line with a wall of the lower opening in the

cabinet, the inclined baffle is again bent at 82 and continues as baffle 84 in a vertical plane, terminating near the upper portion of the base 11. A rear baffle plate 85 is formed by bending a continuation of the wall 84 at right angles and directed toward the wall 7 of the cabinet, thereby forming a rear baffle plate. This plate continues in spaced relation and parallel to the wall 55, and terminates adjacent to wall 61.

Heat deflecting members 86 and 87 are provided and are formed in an angle shape, with the apex of the angle directed towards each other, the said members being in spaced apart relation and in parallel relation to the walls of the cabinet.

It should now be noted that the above described members, baffles and walls, provide flues, chambers and air insulating ducts, each member has an important bearing on the other, and the reasons for the design and construction will become apparent as the description of the intermittent absorption refrigerator system and the location of the various parts progresses.

Referring now to Fig. 3 and Fig. 4, it is deemed advisable to describe in detail and at some length the design and construction of the refrigerating unit per se.

It will be noted upon examination of Fig. 3, that it illustrates a complete intermittent absorption refrigerating unit, with the exception of the heating means and a brine tank.

The refrigerating unit comprises a generator absorber 101, and is preferably arranged in a horizontal and parallel relation to the major portion of the unit, however, the said generator absorber may be placed in various positions in relation to the unit without departing from the scope of the present invention.

The said generator absorber is provided with a depending conduit 102 which is provided with a bend 103, and forms a series of horizontally spaced apart circulatory coils 104, the other end of which terminates in the form of a U shaped loop 105, and terminating in an up leg 106 which is in open communication with the said generator absorber. A main supply conduit 107 is secured to and in open communication with an upper portion of the generator absorber, and continues upwardly and forming an inverted U portion 108, returning downwardly and terminating in a trap 109. A second supply conduit 111 is in open communication with the trap 109 and terminates in a rectifier 112 and near the upper portion thereof, a rectifier return conduit 113 is secured to and in open communication with the lower portion of the rectifier 112 and in open communication with the trap 109, a third supply conduit 114 is in open communication and secured to the rectifier and terminating in an inclined header 115. The said header being secured to and in open communication with the upper portion of an evaporator 116. A condenser supply conduit 117 is also in open communication and secured the header 115 and having its other end terminating in an up leg 118 of a U shaped trap 119. One leg 121 of the trap terminates in a condenser receiver 122 and is in open communication and secured thereto, the leg 118 continues into a horizontal series of spaced apart coils 123 preferably in an inclined relation to the base of the unit, after which the coils terminate into the condenser receiver and are secured and in open communication therewith.

A return conduit 124 having its upper end in open communication and secured to the header 75

115 and the lower end terminating in a leg of the U shaped generator absorber circulatory coil trap 105 and in open communication therewith and secured thereto.

5 It will be noted that the circulatory coil 104 for the generator absorber is provided with spaced apart heat conducting fins 125 and preferably provided with a metal alloy of low resistance to heat transfer.

10 It should now be noted that the generator absorber circulatory coils 104 are provided at their loop ends with supporting means 126 which are secured thereto at one end, and the other end secured to an angle member 127. It will be noted 15 that the angle is provided with its legs 128 directed inwardly from the coil loop, thus providing a slidable rail means for supporting the said unit. It should also be noted that the condenser circulatory coils 123 are provided with heat exchange fins 129, and it should be further noted 20 that a portion of the coils are supported on the angle member 127.

25 A trap return conduit 131 having its upper end in fluid communication with trap 105 and secured thereto, the lower end of said conduit terminating in a dome member 132. Another conduit 133 is also in open communication with the said dome member projecting thru the lower portion of the generator absorber and terminating in a U shaped 30 trap 134, having the other leg 135 secured to and in open communication with the said generator absorber.

35 Depending from and in open communication with the evaporator 116 are supply conduits 136 and 137. It will be noted that the conduit 137 is of greater diameter than conduit 136 for the purpose of providing therein a drain back conduit 138 which projects upwardly and through the evaporator, after which it forms an inverted 40 U shaped member 139, the lower end of the said drain back conduit terminating in the dome section 132.

45 Secured to and in open communication with the supply conduits 136 and 137 are freezing coils 139, 140, and 141. It will be noted that the said freezing coils project outwardly from the supply conduits in a horizontal plane, and it will be further noted that the freezing coils are formed in U shape.

50 A closure plate 142 is provided thru which the freezing coils project, and is located in spaced apart relation to the supply conduits. It will be noted that the closure plate is provided with an offset edge portion 143, the said closure plate 55 offset portion being provided with spaced apart holes 144. The said holes being so arranged to register with the holes 40 provided in the rear wall 43 of the food compartment. A gasket 145 of insulating material is provided for the offset portion of the closure plate, and is provided with spaced apart holes therein which register with the holes 144 of the said plate.

55 The insulated L shaped block 48 which was referred to earlier in this specification, has contained therein the evaporator, supply conduits and a portion of the freezing coils. This insulation block is so formed that it completely fills the space unoccupied by the insulation 47, and is removable as a unit with the evaporator supply legs and freezing coils of the system. It should further be noted that the closure plate 142 abuts a portion of the front face of the said insulating block, and the offset portion 143 is imbedded in the insulation block, thereby providing efficient

insulation around and at the rear of the said closure plate.

60 Bolts 146 are inserted thru the closure plate holes and also thru the holes 40 in the rear wall of the food chamber, the gasket 145 sealing the contacting parts thereof, and bolts 146 securely holding the closure plate in position.

65 The chamber walls 65 provide a space and house a fuel oil burner 151 or similar heating device such as a gas burner or the like. The said fuel oil burner is preferably of the conventional type, being mounted on a fuel supply conduit 152 which is secured to the base 11 by securing means 153 and 154. It will be noted that the fuel supply conduit forms a semi-reservoir, the 10 operation of which will be described later.

70 A fuel control mechanism 155 is associated with a conventional overflow valve mechanism 156, the outlet of which is in fluid communication with the reservoir 152. A fuel tank 157 is provided with a fuel conduit between the said tank and the control mechanism 155. (The conduit is not shown.)

75 It will now be seen from the above description that the refrigerator cabinet is provided with several compartments, flues and air flow insulation means, and so arranged that each compartment, flue and air flow insulation means provide space and air flow for the efficient operation of the present invention relating to an air cooled intermittent absorption refrigerating system.

80 As has been stated, the refrigeration unit as illustrated in Fig. 3 is supported on angle iron members 127 and it should be further noted that the said angle iron members are so spaced as to 85 slidably engage the flange member 22 of the cabinet.

85 It should also be noted that the generator absorber 101 may be provided with heat transfer pins 159 securely associated therewith and placed 40 around the longitudinal portion thereof.

90 In assembling the unit, the various members are placed in their respective positions, including the generator absorber, circulatory coils therefore, the various conduits associated with the generator absorber, the rectifier, evaporator condenser and coils therefore, the supply legs and freezing coils, closure plate therefore and the insulation surrounding the evaporator, supply legs and a portion of the freezing coils. In 95 the present system all assembly connections are welded, using any of the conventional welding methods. As above stated, the entire unit is supported upon a base comprising angle iron portions, and the unit rigidly secured thereto by 55 means of supports.

100 Before placing the unit in the cabinet, the baffle wall 63, together with the baffle wall 58 and wall 66 are placed over the generator absorber. The stack member 76 including the inclined baffle 60 portion 81 and rear baffle wall 85 are next placed in position over the circulatory coils 104 and 123. The entire unit including the housings and stack, are moved inwardly and in slidable relation with the base portion of the cabinet to position in 105 the cabinet. The directional baffle 56 is then secured in place as illustrated in Fig. 11. It will now be noted that a compartment A is formed, in which is located the fuel supply tank 157, conduits and fuel control mechanism 155 and 156.

110 Compartment B, Fig. 12 contains the generator absorber completely housed on all sides, and having the bottom portion thereof open, permitting air to be drawn therethrough by means of the heat applied to the generator absorber.

The upper portion of the chamber B is provided with the flue member baffle wall 63. It will be noted that the baffle wall 55 terminates below the baffle wall 63, providing an opening C therebetween, through which the heat from chamber B may pass into and naturally upwardly into compartment D and through stack E. The heat in its movement drawing air through the circulatory coils for cooling the same. The compartment D having an open bottom portion.

The rear baffle wall 85 being in spaced apart relation with the wall 55 provides an air space therebetween through which air is drawn, thus producing air insulation means, and thus preventing heat transfer from compartment B to compartment D.

The rectifier 112 is placed in compartment F, Fig. 13 which is formed by the wall of the flue member 16, the back wall 18 and the side wall 6 of the cabinet. The bottom portion of the said compartment F is formed by the inclined baffle 81 which directs the heat from the circulatory coils into the flue E, the bottom portion beyond the said coils being open to the atmosphere. The object of placing the rectifier 112 in a separate and cool flue portion is to prevent the heat from the burner supplying heat to the generator absorber from effecting the dehydrating of the vapor in the said rectifier, and provides for more efficient cooling of the same.

The passage H provides a flue through which cool air is drawn, and thereby forms an efficient insulating means between the mechanism of the unit and the food chamber.

A flue cover member 159 being formed of a mesh screen 161 or similar material and provides a housing over the flue E, F and H, the purpose of the said cover is for the exterior styling and performs no part in the operation of the system.

A modification of the condenser and cooling coils therefore is illustrated in Fig. 16 and Fig. 17.

The modification as applied to the present invention includes a series of condenser coils 162 and 163, and is provided with heat transfer fins 164 of material having low heat resisting qualities. The said coils are inclined downwardly with respect to each other, providing means for gravitational flow through the said coils, the end 165 of the said coil terminates in a sump 166 or depressed portion of a condenser receiver 167. It will be noted that the inclination of the condenser coils is limited to a slight angle from the horizontal thereby providing a slow down grade which the condensed vapor will travel to the receiver 167.

Although the function and operation of the present invention will be understood by those skilled in the art, and could be simply described as an intermittent absorption refrigerating system of the 1-3-2 type, it is believed best to now fully describe the function and operation of the said invention, in order to more especially point out the important mechanisms and also to clearly describe the modifications as illustrated in Fig. 17 and Fig. 18.

In the operation of the present invention heat is applied to the generator absorber in which is contained a bi-fluid preferably ammonia water solution. The ammonia is driven off from the water by means of the applied heat of the burner, in the form of ammonia vapor, in which and at times is contained a relatively small amount of water, the vapor passes up through the conduits into the trap, and then to the rectifier wherein any water contained in the vapor is separated in

the rectifier, the water returning to the trap and the vapor conveyed to the evaporator filling the same, as the pressure due to the continued heat applied to the generator absorber is increased the vapor passes down in the conduit to the circulatory coils, constituting the condenser, is therein condensed, and flows under pressure to the condenser receiver, the condensed vapor thereafter continues to circulate through the condenser coils and back into the said receiver.

At the expiration of the heating period, i. e., heat off, the pressure in the system is reduced. However, in the meantime a pressure is built up in the condenser receiver, after the pressure in the system is reduced, the condensed vapor, now a liquid is forced back through the condenser conduit and empties into the evaporator, filling the same with a strong solution of ammoniacal liquor. The refrigerating cycle now starts to function. The liquor in the evaporator obviously fills the supply conduit and the freezing coils. During the refrigerating cycle the heat in the food chamber is absorbed by the liquor in the freezing coils and boiling therein, and boiled off vapor returns to the remaining water in the circulatory coils and the absorber. The water having a high affinity for ammonia quickly absorbs the vapor and in this absorption action forces a circulation through the circulatory coils back to the absorber. During the generating cycle a small amount of water will carry over into the evaporator, and obviously locates near the bottom of the supply conduits and freezing coils. If this water is permitted to build up in the freezing coils and supply conduits, the system will become ineffective, therefore a drain back conduit is provided. The said drain back occurs during the early portion of the generating cycle, and the method used and mechanism therefore is fully described and covered in U. S. Patent No. 2,092,733 issued September 7, 1937, to Edward Gruber and assigned to Allyn Laboratories, Inc.

The modification of the condenser as illustrated in Fig. 17 and Fig. 18 provides for a receiver below the condenser coils, i. e., the vapor is condensed before reaching the condenser receiver, the vapor and liquid circulating only through the coils before reaching the said receiver, thereafter remaining in the receiver and no further circulation occurs.

What I claim is:

1. A refrigerating cabinet having a food chamber, insulation surrounding the said chamber, a mechanism compartment at the rear of said food chamber, an opening in the rear wall of the food chamber, refrigerating mechanism including an evaporator, supply legs depending therefrom, horizontal freezing conduits secured to and in open communication with said legs, a metallic plate greater in dimensions than the opening in the rear wall of the food chamber, the said freezing conduits projecting thru said plate and rigidly secured thereto, the evaporator being connected to the balance of the system by conduits, the said evaporator and supply legs being completely enclosed in an L shaped insulating casing, the freezing conduits being inserted into the food chamber thru the opening therein and the metallic plate forming a closure for the opening in the rear wall and rigidly secured thereto.

2. In an intermittent refrigerating system including a generator absorber, a rectifier, an evaporator, conduits depending therefrom and horizontal freezing coils secured to said conduits and a condenser, all connected in operative relation;

- the generator absorber and condenser being located at the base of the unit with the condenser positioned at a lower level than the said generator absorber, the evaporator being located at the top of the unit and the rectifier intermediate the evaporator and generator absorber, the whole assembled refrigerating system being removably secured to and in a refrigerator cabinet.
3. In a refrigerating cabinet, having a food chamber, insulation surrounding the said chamber, a mechanism compartment at the rear of said chamber and a mechanism compartment under the chamber, an opening in the rear wall of the food chamber, refrigerating mechanism including a generator absorber, rectifier, evaporator and condenser operatively associated by means of conduits, depending conduits from said evaporator, and horizontal freezing coils secured to said depending conduits, a closure plate of greater dimensions than the opening in the food chamber, the freezing coils projecting thru said plate and secured thereto, an insulated casing completely enclosing the evaporator and depending conduits, the entire refrigerating mechanism being movable as a unit in operative position into the mechanism compartments and the food chamber, the closure plate being secured to the rear wall of the food chamber adjoining the opening therein and thereby supporting the freezing coils and depending conduits thereto, the evaporator being supported in the compartment above the chamber the remainder of the system being supported by the generator absorber and condenser, the latter being located in the mechanism compartment below the chamber.
4. In an intermittent absorption refrigerating system, including, a generator absorber, horizontal spaced apart circulatory coils in open communication with the said generator absorber, a rectifier, an evaporator having depending conduits therefrom and horizontal freezing coils secured to the said conduits, a condenser located adjacent the generator absorber and connected by conduit to the evaporator, horizontal spaced apart cooling coils below and in open communication with the said condenser, the said condenser coils being located below and in spaced apart relation to the generator absorber circulatory coils, the said generator circulatory coils thereby being located in position to induce air flow through the condenser circulatory coils, and the entire refrigerating unit being removably secured to and in a refrigerator cabinet.
5. A refrigerator cabinet, having a food chamber therein, a mechanism compartment at the rear of the food chamber, and a mechanism compartment below the food chamber, refrigerating mechanism including, a generator absorber, a rectifier, an evaporator, and a condenser all operatively associated by means of conduits, the evaporator being provided with depending legs and horizontal freezing coils secured to said legs, an opening in the rear wall of the food chamber through which the freezing coils enter the food
- chamber and means for securing the freezing coils to the said rear wall of the food chamber, and horizontal spaced apart circulating coils associated with the generator absorber, horizontal spaced apart circulating coils associated with the said condenser and located below the same, the said condenser coils being mounted below the said generator absorber coils, and the said refrigerating mechanism forming an integral unit removably secured to and associated with the cabinet and the several mechanism compartments, and all connected in operative relation.
6. In a refrigerating cabinet having a food compartment, an opening in the rear wall of the compartment, refrigerator mechanism of the absorption type, including a generator absorber, an evaporator and a condenser, all connected in operative relation, the said evaporator having depending supply legs, and horizontal freezing coils secured to said legs, a closure plate through which the freezing coils project, and to which the said coils are secured, the said plate being larger than the opening in the rear wall of the cabinet, and means for securing the said plate to the rear wall of the food compartment, the entire refrigerator mechanism being removable from said refrigerating cabinet as a unit.
7. In a refrigerating cabinet having a food compartment, an opening in the rear wall of the compartment, refrigerator mechanism of the absorption type, including a generator absorber, an evaporator and a condenser, all connected in operative relation, the said evaporator having depending supply legs, heat insulating material surrounding said evaporator and supply legs, and horizontal freezing coils secured to said legs, a closure plate through which the freezing coils project, and to which the said coils are secured, the said plate being larger than the opening in the rear wall of the cabinet, and means for securing the said plate to the rear wall of the food compartment, the entire refrigerator mechanism being removable from said refrigerating cabinet as a unit.
8. In a refrigerating cabinet having a food compartment, an opening in the rear wall of the compartment, refrigerator mechanism of the absorption type, including a generator absorber, an evaporator and a condenser, all connected in operative relation, the said evaporator having depending supply legs, heat insulating material encasing the said evaporator and depending supply legs, spaced horizontal freezing loops communicating with said legs and extending outwardly therefrom, a closure plate through which the freezing coils project, and to which the said coils are secured, the said plate being larger than the opening in the rear wall of the cabinet, and means for securing the said plate to the rear wall of the food compartment, the entire refrigerator mechanism being removable from said refrigerating cabinet as a unit.
